UNITED STATES PATENT OFFICE

2,653,055

DISPENSING AND MIXING VALVE

Frank Welty and Raymond Welty, Youngstown,
Ohio, assignors to Carbonic Dispenser, Inc.,
Canfield, Ohio, a corporation of Ohio

Application June 6, 1949, Serial No. 97,409

17 Claims. (Cl. 299—145)

1

This invention relates to the art of dispensing liquids and more particularly to improved valves and faucets for dispensing either carbonated liquids, such as beer or carbonated water, or mixtures of carbonated water and flavoring syrups, such as ginger ale and cola drinks, for example. In apparatus of this nature it is highly desirable to effect the transference of the carbonated liquid from a supply line to the customer's glass with a minimum of loss of the absorbed gas to provide a drink of an adequate and acceptable degree of carbonation and this is true regardless of whether the liquid is served in its initial state or is mixed with flavoring extracts or syrups in the dispensing process. The loss of carbonation has always presented a serious problem in the dispensing of carbonated liquids and is particularly aggravated when mixing of the carbonated liquid with other liquid occurs in the dispensing process. It is the primary object of this invention to provide an improved dispensing valve and faucet for handling carbonated liquids in which a minimum of carbonation is lost in the transference of the liquid from a supply line to the customer's glass. It is another object of the invention to provide an improved dispensing faucet for carbonated liquids which is operative either with or without a closely connected shut-off valve to dispense such liquids with a minimum of loss of carbonation.

In the dispensing of carbonated beverages which are normally retained and supplied under considerable pressure it is recognized that the pressure of the liquid must be reduced before it issues from the nozzle of the dispensing faucet since otherwise the excessive agitation which takes place in the glass causes excessive foaming and dispeeling of the carbonating gas. To accomplish this suitable pressure-reducing restricted passages of adequate length are provided and this principle is utilized in the present invention. In the present invention, however, the effective cross-sectional area of the restricted passage is adjustable but normally fixed and has no operating connection with the shut-off valve so that uniform operation and minimum de-carbonation is obtained however the valve is manipulated. Further, we provide an enlarged surge chamber at the exit end of the passage to receive the liquid now reduced to low pressure and the arrangement is further such that the liquid flows out of this chamber into the customer's glass solely by gravity, thereby avoiding any appreciable velocity to cause excessive impingement and agitation.

A further object of the invention is the provision of an improved dispensing and mixing faucet having the desired characteristics as regards carbonated beverage dispensing pointed out above but which is operative to adequately mix in such beverage flavoring extract or syrup without reducing the carbonation. This further

2

object is accomplished by providing separate valves for injecting the extract or syrup into a mixing chamber and by utilizing a low velocity flow of the carbonated liquid from the surge or collecting chamber to wash the extract or syrup away from the inlet valves and to keep such valves clean. In this manner high velocity impingements which reduce carbonation are avoided and, further, the valves are kept clean so that the dispensing system may be utilized to dispense different mixtures or successive operations without inter-contamination.

A still further object of the invention is the provision of an improved mixing and dispensing faucet having the characteristics enumerated immediately above which is operative with remotely disposed supply control valves for both the carbonated liquid and the flavoring syrups or extracts for use in automatic dispensing equipment, for example.

Yet another object of the invention is the provision of an improved dispensing faucet of unitary self-contained construction by which either an unmixed carbonated liquid or a selected mixture of such liquid and another liquid may be dispensed in an expeditious and more or less automatic manner.

The above and other objects and advantages of the invention will become apparent upon consideration of the following detailed specification and the accompanying drawing wherein there is disclosed a certain preferred embodiment of the invention.

In the drawing:

Figure 1 is a front elevation, partly in section, of a mixing and dispensing valve constructed in accordance with the principles of our invention;

Figure 2 is a vertical section taken along the line II—II of Figure 1;

Figures 3 and 4 are horizontal sections taken along the line III—III of Figure 2 and IV—IV of Figure 1, respectively; and

Figure 5 is a view similar to Figure 2 but showing the installation in the valve assembly of a high velocity water jet device.

The illustrated valve assembly comprises a unitary cylindrical block 10 of non-corrosive material, such as stainless steel for example, which is recessed at 11 in its side wall for being supported on the outer free end of a tubular support

12. As shown in Figure 2, the top and bottom ends of the block 12 are generally horizontal and parallel and extending downwardly from the top end thereof is a bore 13 in which is slidably received a plug 14, the same being rigidly secured

therein by a set screw 15. In the outer periphery of the plug 14 there is machined a circumferential groove 16 which is aligned with the passageway 17 formed in the block 10 and communicating with a vertically disposed tapered bore 18 also formed in the block 10. The tapered bore 18 extends upwardly from an enlarged recess 19

formed in the bottom wall of the block 10. Closing off this last named recess is a plate 20 having a threaded aperture 21 in which is received the threaded head portion 22 of a tapered restriction plug 23, the body portion of which is received in the tapered bore 18.

The lower end of the plug 14 is spaced upwardly from the bottom end of the bore 13 to provide a space 24 into which discharges carbonated water supplied by a conduit 25 extending through the tubular member 12. To prevent leakage of water from the space 24 past the plug 14 we provide a plurality of sealing rings 26 which are received in annular grooves formed in the side wall of the plug 14. Plug 14 is provided with three longitudinally extending but diametrically related bores in each of which is received a valve plunger having a shank portion 27 and an enlarged head portion 28 provided with a sealing ring to prevent leakage through the top of the plug 14, as will be understood. To the lower end of each of the shank portions 27 is rigidly secured a thimble 29 having a flat annular upper surface in which is machined an annular groove to partially receive a sealing ring of the O type and the upper surface of this sealing ring is adapted to bear against the bottom surface of the plug 14 as indicated in Figure 1. Plug 14 is provided intermediate its top and bottom ends with a diametrically extending bore 30 which is in communication at its ends with the groove 16 and since the shanks 27 of the valve plungers are of smaller diameter than the longitudinal bores formed in the plug 14 it will be obvious that upon downward movement of any of the three valve plungers and the consequent separation of any of the thimbles 29 from the lower surface of the plug 14 that water under pressure in the space 24 will pass upwardly into the bore 30, thence into the groove 16, thence through passage 17, and thence through the interstice between bore 18 and plug 23 into the space 19. The three valve plungers slidably received in the plug 14 are biased to upward or valve closing positions by the coil springs 31 which are compressed between the bottom wall of the space 34 and the thimbles 29.

The block 10 is further provided with a pair of longitudinally extending bores 32 on diametrically opposite sides of the bore 13 to slidably receive valve plungers 33 and as shown in Figure 1 the bores 32 are enlarged at their upper ends as shown at 34 and are enlarged at their lower ends as shown at 35. The upper end of each plunger 33 is headed, as shown, and interposed between the head and the lower end of the bore enlargement 34 is a sealing ring 35 and a coil spring 37 whereby the plunger is urged to upper position and whereby the sliding joint between the plunger and the body member 10 is sealed against fluid leakage.

Surrounding the lower end portion of each of the plungers 33 in concentric spaced relation therewith is a tubular valve member 38 rigidly secured to and depending from the block 10 and rigidly secured to the lower end of each of the plungers 33 below the lower end of the tube 38 is a valve head 39 which has a flat annular upper surface in which is machined an annular groove for the partial reception of a valve sealing ring 40 which is adapted to engage the flat lower end surface of the tube 38. The coil spring 37 urges the plunger 33 upwardly and the sealing ring 40 into pressure engagement with the lower end of the tube 38. The bore enlargement 35

is provided with a communicating passage 41 formed in the body member 12 and connected with such passages (one for each of the bore enlargements 35) are the conduits 42 and 43 also housed in the tubular member 12. It will be understood that in actual practice the conduits 42 and 43 will be filled with desired drink flavoring extract under pressure so that upon downward movement of either of the plungers 33 one or the other flavoring extract will be discharged through one of the passages 41, connected bore enlargement 35 and associated valve comprised of the members 38 and 40. Rigidly secured in a suitable aperture formed in the plate 20 is an open-bottomed cup 44, the lower end of which surrounds the lower end of the tube 38 and it will be understood that a similar cup will be provided for the duplicate extract valve employed on the opposite side of the assembly. It should also be particularly noted that the cup 44 is of considerable depth and that the valve 39, 40 is positioned a substantial distance below the space 19. Plate 22 is also formed with a plurality of apertures 45.

Rigidly secured to diametrically opposite side edge portions of the top surface of the block 10 by means of the screws 46, for example, is a pair of supports 47 which are apertured to support the ends of a pivot pin 48. Pivotaly mounted on the pin 48 are three operating levers 49, 50 and 51, each having an operating knob at its upper end, as shown, and each of which is adapted to be independently operated. The lower ends of the levers 49—51 are each provided with a foot 51 to engage the top surface of the plug 14 or the top surface of the body member 10, as the case may be, to limit the backward tilting movement of the levers and the lower ends of the levers are further provided with integral cam surfaces 52 to operate the various valve plungers upon forward tilting movement of the levers. Thus, the lower or base portion of the lever 50 is made quite narrow so that its cam surface 52 engages only the middle one of the water valve plungers 28 housed in the plug 14. The base of the lever 51 is widened, as shown at Figure 1, and is provided with a pair of spaced integral cam elements to engage and operate both one of the side water valve plungers 28 and one of the syrup valve plungers 33. It will be understood that the lever 49 is identical with the lever 51 except for being in opposite hand so that the other of the side water valve plungers and the other of the syrup valve plungers may be simultaneously actuated.

In actual practice the two cam surfaces on the levers 49 and 51 are so formed and/or relatively oriented that as either of these levers are moved forwardly the associated water valve is first opened, after which the associated syrup valve is opened and upon the levers being moved back to "off" positions the syrup valves are closed ahead of the water valves so as to allow thorough washing off of the syrup valve discharge ports after each use of the same.

To complete the assembly of the valve shown in Figures 1-4, a conical-shaped discharge funnel 52 is secured to the lower end of the body member 10 and a cap member 53 is secured to the upper end of the member 10 to house the bases of the levers 49—51 and the pivot pin therefor. Suitable slots 54 are formed in the cap member 53 to allow movement of the levers 49—51.

In operation, the body member 10 of the valve assembly is mounted on the tubular carrier 12.

in such manner that the principal axis of the valve assembly is vertical and so that the levers 49-51 are to be moved toward the operator in dispensing the connected fluids. Assuming a source of carbonated water to be connected to the conduit 25 and different flavoring syrups to be supplied under pressure to the conduits 42 and 43 it will be obvious that if it is desired to dispense only carbonated water the same can be accomplished by moving only the lever 50. When it is desired to dispense a mixed drink of carbonated water and one or the other of the flavoring syrups, one or the other of the levers 49 or 51 is moved to dispense carbonated water and syrup in predetermined proportions. The proportioning is controlled by the relative sizes of the valve orifices or by the pressures applied to the respective liquids, as will be understood.

The large space 19 provided in the lower end of the body member 10 is of extreme importance in the operation of the valve of our invention since it provides, in effect, a surge chamber whereby the high velocity of the carbonated water issuing past the restricting plug 23 is dissipated, thereby reducing the carbonated water pressure substantially to atmospheric pressure and quieting the turbulence and foaming in the water.

The latter characteristic is aided by the further fact that in the normal operation of the valve the chamber 19 as well as the cups 44 rapidly become substantially filled with water very soon after the opening of the water valve or valves so that the high velocity carbonated water leaving the restricted passage becomes entrapped in the body of water contained in the chamber 19. The impingement of the high velocity flow into the body of entrapped water reduces the velocity head of the carbonated water to zero without loss of carbonation.

From the space 19 the water falls easily by gravity through the ports 45 and through the open lower ends of the cups 44 past the lower ends of the syrup nozzles 38 and the water flows easily but solidly out of the funnel 52 into the consumer's glass. The substantial cross-sectional areas of the annular openings at the bottom of the cups 44 are substantially greater than the annular orifice provided between the bore 18 and the plug 23 so that no appreciable pressure can develop in the space 19 and since such annular openings at the bottom ends of the cups 44 are considerably below the plane of the plate 20, substantially all the water discharged will be emitted through the cups 44. This insures not only the adequate washing away and intermixing of all the syrup discharged from the nozzles 38 but also a maximum retention of carbonation in the water.

We have also found that loss of carbonation is further reduced by avoiding abrupt changes in the direction of flow of the carbonated water after the same leaves the restricting passage and is reduced to atmospheric pressure. After the pressure is taken off the water the tendency of the gas to escape out of it is much more pronounced. In our valve abrupt changes in the direction of flow are avoided by allowing the water to drop substantially straight down into the customer's glass.

It should also be noted that a further function of the cups 44 is to provide stored bodies of water which, after closure of both the syrup and water valves, discharge downwardly about the syrup valves to thoroughly wash the same

and to clean any syrup stains from the inner surface of the funnel 52.

In the embodiment of the invention shown in Figure 5 we incorporate in the valve assembly of Figures 1-4 an arrangement for injecting a high velocity stream of carbonated water vertically downward through the lower opening in the funnel 52 for the purpose of effecting a mixing and foaming in a customer's glass as is desirable in some instances. For this embodiment we provide a plate 20' which generally corresponds to the plate 20 in the first described embodiment but which is provided with means to support a centrally disposed tapering tube 56 having a high velocity jet 57 formed in its lower end. The block 10 is apertured as at 58 to receive a small tube 59 which extends downwardly through the space 19 into communication with the open upper end of the tube 56. There is provided a plug 14' identical in all respects with the plug 14 of the first described embodiment except for an additional bore 60 to slidably receive a connecting rod 61. Secured to the lower end of the rod 61 and housed in the space 24 is a valve member 62 which carries at its lower end a sealing ring 63. Upon the rod 61 and fitting 62 being moved upwardly the port leading into tube 59 is uncovered and carbonated water under pressure can pass directly from the space 24 downwardly out of the jet 57. Fluid pressure in the space 24 normally holds the valve members 62, 63 in tightly closed position.

A modified form of center operating lever 50' is used to provide an interconnection between this central lever and the rod 61 whereby the rod is moved upwardly when the lever 50' is tilted backward from its vertical position (there being a footstop on the lever 50') but whereby forward tilting movement of the lever 50' will not move the rod 61 but will result in opening of the water valve plunger 28 as before. The required lost motion interconnection between the lever 50' and the rod 61 may consist of a ball 64 on the upper end of the rod 61 riding in an arcuate groove 65 formed in the lever 50' and a slot 66 to receive the upper end portion of the rod 61 as the lever is rotated. It should be apparent that a valve assembly constructed according to Figure 5 is operative in the regular manner as the valve of Figures 1-4 and when it is desired to provide the high velocity water jet it is only necessary to move the center lever 50' rearwardly from its vertical position to thereby open the valve 62, 63.

The adjustable restricting plug 23 may also be utilized to determine the rate of flow of the carbonated water as will be understood, and this rate of flow will be more or less constant regardless of the extent of opening of any of the three water valves beyond a certain minimum extent. This arrangement insures the gradual reduction of water pressure, under all operating conditions, without spraying or impingement, so that there is a minimum of loss of carbonation regardless of whether only water is dispensed or a mixture of the water and a flavoring syrup.

The cam surfaces on the levers 49-51 and 50' are preferably so formed that the levers will remain either in their fully closed positions or in their fully open positions to which they have been last moved. This enables an operator to fill a large number of glasses in a short period of time since he will have both hands free to manipulate and handle the glasses.

It should now be apparent that we have provided an improved dispensing and mixing faucet which accomplishes the objects initially set out.

Primarily, the features of construction of the valve assembly are directed to the dispensing of carbonated liquids, either water alone or a mixture of water and flavoring syrup, in a manner resulting in small loss of carbonation in the water or liquid. The valve assembly of the invention is further operative to adequately mix in the water dispensed a suitable flavoring extract or syrup without appreciable loss of carbonation in the water and without cross-contamination when a plurality of different syrups are dispensed in the same valve assembly. The invention further provides a dispensing and mixing valve assembly of efficient practical utility which is rugged in character and capable of long periods of service without adjustment or maintenance.

The above specifically described embodiment of the invention should be considered as illustrative only as obviously many changes may be made therein without departing from the spirit or scope of the invention. Reference should therefore be had to the appended claims in determining the scope of the invention.

We claim:

1. In a valve assembly for mixing and dispensing carbonated beverages, the combination of a valve body having a first inlet for carbonated water and a second inlet for flavoring syrup, a valve tube secured to and depending from said body and being in communication with said second inlet, a valve rod extending vertically through said tube and carrying a valve member at its lower end adapted to engage the lower end surface of said tube, a water valve in said body communicating with said first inlet, an enlarged surge chamber in the lower portion of said body and surrounding a portion of said tube, said chamber having an opening in its bottom wall disposed about said tube, and means in said body providing a restricted passage between the outlet of said water valve and said surge chamber.

2. A valve assembly according to claim 1 further characterized in that said tube extends below said bottom wall, and further including an open-bottomed cup secured in said aperture and having its lower or discharge end positioned adjacent said valve member and concentric therewith.

3. A valve assembly for mixing and dispensing carbonated beverages comprising in combination a valve body supported from its side wall; a plurality of valve tubes secured to and depending from said body in widely spaced relation, fluid inlet passages in said body communicating with the spaces in said tubes, valve rods extending vertically through said tubes and each carrying a valve member at its lower end adapted to be moved into engagement with the lower end of the valve tube, a bore in said body extending downwardly from the top wall thereof intermediate said tubes, a valve plug fixed in the upper portion of said bore, a water inlet passage in said body communicating with the space in the lower end portion of said bore, a plurality of water valves mounted in said plug, each having an inlet communicating with said space, a restricted passage in said body communicating with the outlets of each of said water valves, an enlarged surge chamber in the lower portion of said body and disposed about the lower end portions of said tubes to receive carbonated water issuing from said restricted passage, outlets in the bottom wall of said chamber disposed about said valve members, and a plurality of operating levers pivoted on the top of said body, one of said levers being connected to a water valve only, and the other of

5 said levers each being connected to both a water valve and one of said valve rods.

4. A valve assembly according to claim 3 further including a funnel secured to and depending from the bottom end of said body, said funnel enclosing all of said valve members.

5. A valve assembly for mixing and dispensing carbonated beverages comprising in combination a body supported from its side wall, a plurality of valve tubes secured to and depending from said body in widely spaced relation, inlet passages in said body leading into said tubes, a tapered bore extending upwardly from the bottom of said body, a tapered plug adjustably secured in said bore to provide an adjustable but normally fixed restricted passage, a water valve in said body having an outlet communicating with the upper end of said passage, an inlet passage in said body for said water valve, a valve rod in each of said tubes carrying a valve member at its lower end adapted to close off the lower end of the tube, and operating levers pivotally mounted on the top of said body for operating said water valve and any one of said valve rods simultaneously.

6. A valve assembly according to claim 5 further including an enlarged surge chamber in the lower end portion of said body and communicating with the lower end of said restricted passage, and outlets from said surge chamber disposed about the lower ends of said valve tubes.

7. A valve assembly according to claim 6 further including a funnel-like enclosure at the lower end of said body for containing said valve members.

35 8. Apparatus for mixing and dispensing carbonated beverages comprising a body member having a first inlet for carbonated water and a second inlet for flavoring syrup, a tube secured to and depending from said body and being in communication with said second inlet, a valve to control the discharge of syrup from said tube, an enlarged water entrapping chamber in the lower portion of said body member and surrounding said tube, a restricted passage in said body member interconnecting said first inlet and said enlarged chamber, said chamber having a bottom wall with an opening therein surrounding said tube, and a water holding cup secured in said opening in tapering relation therewith and having a centrally disposed discharge opening at its bottom end disposed concentrically about the discharge end of said tube and closely spaced therefrom.

55 9. A valve assembly for dispensing carbonated beverages at either low or high velocity as desired comprising a body member having an enlarged recess in both its top and bottom walls, means to support said body member, a plug in the upper portion of said upper recess and means providing an inlet for the beverage into the lower portion of said upper recess, a valve in said plug and a restricted passage in said body member interconnecting the outlet of said valve with the enlarged recess in the bottom wall of said body member whereby liquid may be valved from said first mentioned recess into said last mentioned recess while having its pressure reduced, a bottom wall for the lower recess having an opening therein for the downward flow of the beverage, a lever pivoted on said body member to operate said valve, a funnel secured to the lower end of said body member to collect and discharge the beverage passing through said opening, a jet tube positioned within said funnel and arranged to discharge through the discharge neck of said

funnel, means providing a liquid passage from said upper recess directly into said jet tube, and a valve operated by said lever for opening and closing said last mentioned passage.

10. In a beverage mixing and dispensing valve assembly the combination of a body member having a pair of inlet ports adapted to be connected to different sources of liquids, a horizontally disposed chamber at the lower end of said body member having an aperture in its bottom wall to discharge liquid, a tube carried by said body member in depending relation and having its lower end terminating substantially in said aperture, means providing communication between one of said inlet ports and the upper end of said tube, a valve rod reciprocably mounted in said tube and carrying at its lower end a poppet-type of valve arranged to close off the lower end of said tube, means comprising a second valve providing communication between the other of said inlet ports and said horizontally disposed chamber, and a lever pivotally mounted on said body member to operate said second valve and said valve rod simultaneously.

11. Apparatus according to claim 10 further including separate means on said lever to operate said second valve and said valve rods, said separate means being arranged in such manner that during movement of said lever in one direction said second valve opens ahead of said first mentioned valve and during movement of said lever in the opposite direction said first mentioned valve closes ahead of said second mentioned valve.

12. In apparatus for mixing and dispensing carbonated beverages a body member having a first inlet for carbonated water and a second inlet for flavoring syrup, a tube secured to and depending from said body and being in communication with said second inlet, a valve at the lower end of said tube to control the discharge of syrup therefrom, an enlarged water entrapping chamber in the lower portion of said body member and surrounding said tube, and a restricted passage in said body member interconnecting said first inlet and said enlarged chamber, said chamber having a bottom wall with an opening therein surrounding said tube.

13. In a valve assembly for mixing and dispensing beverages a body member having a water inlet and a syrup inlet, a tube secured to and depending from said body member and being in communication with said syrup inlet, a valve at the lower end of said tube to control the discharge of syrup therefrom, an enlarged water entrapping chamber in the lower portion of said body member and surrounding said tube, and means in said body member providing communication between said water inlet and said chamber, said chamber having a bottom wall with an opening therein surrounding said tube whereby upon the discharge of water by gravity through said opening the lower end portion of said tube and said valve is washed by the downflow of water.

14. In a beverage mixing and dispensing valve the combination of a syrup valve having a tubular outlet, a water valve, outlet means for said water valve comprising a water-retaining drip cup positioned concentrically about said tubular outlet and forming therewith a reservoir for water, said drip cup and said tubular outlet comprising a restricted outlet passage for water whereby upon closing of said water valve water retained in said drip cup forms droplets about and falls

from the end of said tubular outlet to wash residual syrup therefrom.

15. In a beverage dispensing valve assembly the combination of a casing having a beverage inlet passage and a cavity forming a beverage-entrapping chamber, a valve controlling the flow of beverage through said inlet passage, means providing a restricted passage between said inlet passage and said chamber, said cavity having a discharge aperture the effective cross-sectional area of which is small as compared to the volume of said cavity and which volume is so related to the normal rate of discharge of said restricted passage when said valve is open that during normal operation a quantity of beverage is contained in said chamber to absorb the velocity of the beverage issuing from said restricted passage whereby the beverage is discharged from said assembly wholly by gravity and without substantial loss of carbonation.

16. A valve assembly according to claim 15 further characterized in that said cavity has a bottom wall and said discharge aperture being located in said bottom wall, and further including a syrup inlet passage in said casing and a syrup valve in said casing in communication therewith, and a discharge port for said syrup valve comprising a depending tubular element having an open bottom end positioned within said discharge aperture, the arrangement being such that upon closing of said valves the liquid contained in said chamber operates to wash off said tubular element upon discharge by gravity from said chamber.

17. In a valve assembly for mixing and dispensing a plurality of separate beverages in sequence the combination of a casing having a water inlet passage and a valve connected thereto for controlling the flow of water therethrough, a plurality of syrup inlet passages in said casing and a syrup valve for each of said syrup inlet passages, a syrup discharge port for each of said syrup valves comprising a depending tubular element carried by said casing and having an open bottom end, outlet means for said water valve comprising a water-retaining drip cup positioned concentrically about each of said tubular elements and forming therewith reservoirs for water, said drip cups and said tubular elements comprising restricted outlet passages for water whereby upon closing of said valves water retained in said drip cups forms droplets about and falls from the lower ends of said tubular elements to thereby wash residual syrup therefrom, and a funnel-like discharge nozzle closing off the lower end of said casing and enclosing said drip cups and lower open ends of said tubular elements to collect and direct the discharges from said elements and cups to a centrally disposed discharge point.
